IGNITER FOR GRENADES

André Valère Adrien Mortreux, Mulhouse,
France, assignor to Société Alsacienne
d'Explosifs (Société à Responsabilité Lim-
itée) à Richwiller, Haut-Rhin, France

Application February 12, 1935, Serial No. 6,169
In France April 10, 1934

4 Claims. (Cl. 102—36)

This invention relates to an igniter for grenades, essentially characterized, on the one hand, by the fact that the mechanical part and the pyrotechnical part are entirely independent and are connected only at the time of assemblage and, on the other hand, by the fact that the pyrotechnical part constitutes a unit having a fluid-tightness of its own.

Owing to these two essential features, it is possible to render the manufacture of the mechanical and pyrotechnical parts entirely independent, to keep them separately stored before their assemblage, without any prejudice to the fluid-tightness of the pyrotechnical part, and, finally, to subject the latter, separately, while it is stored or before assemblage, to tests for verifying its fluid-tightness.

Considering these remarkable advantages of the invention, it is to be remembered that, in some known types of igniters the primers and the safety or burning fuse are left uncovered in the part forming the cap of the device, so that their protection is obtained only in precarious conditions by the packings closing the said cap.

In other types also known, the fluid-tightness of the pyrotechnical part is not ensured as long as the assemblage with the mechanical part is not effected, so that any separate storage of the pyrotechnical part is practically prevented, as well as any test resorted to for verifying the fluid-tightness and exclusively carried out on this pyrotechnical part.

The accompanying drawing is an axial section of a form of carrying the invention into practice, given by way of example only and in which, in order to obtain an absolutely fluid-tight pyrotechnical part, all the elements of the same are enclosed within a metal case the mouth of which is finally closed by means which will be particularly described later on.

In the drawing, the entire mechanical part is known *per se*. It comprises,—within a cap 1 externally screw threaded at 1^a for screwing the igniter on the grenade,—a percussion pellet 3 which is subjected to the action of a spring 2 and carries the needle or striker 5. The locking of the percussion pellet is effected by a claw 6^a which, passing in a slot of the striker, presses against the base 3^a of the percussion pellet. The locking claw 6^a is itself rigid with a lever 6, the pivot pin 6^b of which simply rests on two bearings of a fork piece 1^b provided on the head or cap 1. This lever is locked, on the other hand, in the safety position illustrated in the figure, 55 by means of a pin 7 passing through the lever

and through a fork piece 1^c of the head. In this position, a packing 4 is clamped between a bearing portion of the locking lever and the edge of the aperture 1^d through which the claw 6^a enters the cap 1.

This unit, according to the invention, is entirely independent from the purely pyrotechnical part which will now be described.

This pyrotechnical part, separately manufactured and completely fluid-tight, is entirely enclosed within a metal case 12 which carries (in the order indicated in the drawing from top to bottom), the percussion cap 10, the burning tube or delay 13, and the detonator 15.

The cap 10 rests on a support 9, the bottom of which is open and surrounded by a small quantity of a special composition 17, serving as an ignition relay.

The delay 13 is constituted by a burning tube charged with a special powder ensuring a very regular combustion and giving little residue in order that the vent holes 3^b of the percussion pellet 3 should remain unobstructed. This burning tube is inserted at its upper part in a so-called "delay-carrying tube" 11. Under the latter is threaded a cardboard tube 14 on which is engaged the upper part of the detonator 15 which rests against the bottom of the case 12 through a washer 16.

The various constituent elements of the pyrotechnical unit being thus placed in position within the metal case 12, the mouth of the latter is obturated in a rigorously fluid-tight manner by a cover 8 made of a waterproof and malleable material, such as metal, plastic material, etc. 35 This cover, after interposition of a special lute, is beaded between two conical surfaces provided on the case 12 and on the "delay-carrying tube" 11, at their upper end. Owing to the conical shape of the two clamping surfaces, the cover 8 40 is firmly held so that the pyrotechnical part thus closed constitutes a unit having a fluid-tightness of its own.

The assemblage of the pyrotechnical part on the mechanical part is simply effected by beading at 18, which completes the absolute fluid-tightness of the device (mechanical part included). In these conditions, the operation of the igniter remains satisfactory in any circumstances. Particularly, even after remaining for 50 a long time in mud, no wedging of the percussion pellet can occur as is the case, in other systems, owing to the introduction of foreign matters within the cap.

The mechanical part gives to the unit thus 55

constituted its well known advantages. The pyrotechnical part, constituted as a fluid-tight unit, can be preserved intact during a practical indefinite period of time, whether it is fitted on the cap or whether it remains stored before assembly.

I claim:

1. An igniter for grenades comprising: a mechanical part and a pyrotechnical part entirely independent and connected only at the time of assemblage, the pyrotechnical part including a fluid-tight casing, a delay-carrying element within this casing, two sets of conical surfaces provided at the upper part of the casing and of the delay-carrying element, respectively, and a cover made of waterproof and malleable material beaded between both sets of conical surfaces.

2. An igniter for grenades constituted by a mechanical part and a pyrotechnical part entirely independent, the mechanical part comprising a cap with means for securing it on the grenade, a spring percussion pellet carrying a striker, means for locking said percussion pellet and comprising a claw pressed against the latter, a pivoted lever carrying said locking claw, a pin for locking said lever, the pyrotechnical part being and completely fluid-tight and comprising a case containing a percussion cap, a burning tube, a delay tube, a detonator, a delay-carrying tube enclosing the upper part of the burning tube, a cardboard tube on which is threaded the upper part of the detonator, two sets of conical surfaces provided on the upper part of the case and of the delay-carrying tube, respectively, and a waterproof and malleable

cover beaded between both sets of conical surfaces and ensuring to said case a fluid-tightness of its own.

3. An igniter for grenades including a mechanism casing having an open lower end adapted to project into the grenade, a fluid tight tube forming a fuse casing and closed at its lower end, the open end of the tube being fitted in the open end of the mechanism casing, a fluid tight closure for the fuse casing, a fuse in said fuse casing, an explosive cap supported at the end of the fuse casing covered by said closure, said fuse casing being internally of inverted frusto-conical form, and an inverted frusto-conical member in said tube supporting the cap, said cap being provided with a peripheral skirt held between said frusto-conical portions.

4. An igniter for grenades including a mechanism casing having an open lower end adapted to project into the grenade, a fluid tight tube forming a fuse casing and closed at its lower end, the open end of the tube being fitted in the open end of the mechanism casing, a fluid tight closure for the fuse casing, a fuse in said fuse casing, an explosive cap supported at the end of the fuse casing covered by said closure, said fuse casing being internally of inverted frusto-conical form, an inverted frusto-conical member in said tube supporting the cap, said cap being provided with a peripheral skirt held between said frusto-conical portions, and a shoulder in said mechanism casing against which the fuse casing abuts to limit its movement into the mechanism casing.

ANDRÉ VALÈRE ADRIEN MORTREUX.
